GUY ROD GROUNDING CLAMP

David C. Hubbard, Centralia, Mo., assignor to
 A. B. Chance Company, Centralia, Mo., a corporation of Missouri

Application April 10, 1940, Serial No. 328,841

12 Claims.

(Cl. 24—135)

The present invention relates to guy rod grounding clamps, and is particularly concerned with an improved guy rod clamping structure adapted to provide a dependable mechanical and electrical pressure contact between the guy strand or cable and an anchor rod, where anchor rods are used as grounding rods.

Another object of the invention is the provision of an improved guy rod grounding clamp adapted to maintain the substantially cylindrical shape of the guy strand or cable, for the purpose of avoiding the mashing or flattening of the cable, which would otherwise tend to destroy the cable and place unnecessary strain on certain of the parts of the cable.

Another object of the invention is the provision of an improved clamping device for a guy rod, which, by virtue of its firm gripping action, tends to eliminate the abrasive action which occurs on the guy cable and anchor rod, due to causes such as vibrations and slackness in the guy cable.

Another object of the invention is the provision of an improved electrical connecting device for guy rods and guy cables which assists the usual guy cable clamps in securing the cable to the anchor rod and provides additional security and strength for the installation.

Another object of the invention is the provision of an improved electrical connecting device for guy rods and cables which is simple in structure, capable of economical manufacture, sturdy, and adapted to be applied with a minimum amount of labor.

Another object of the invention is the provision of improved electrical connecting devices for guy rods and guy cables which include connecting members adapted to be wedged into engagement with the cable by means of a bolt or other threaded means so as to assure a good electrical connection.

Another object of the invention is the provision of improved electrical connecting devices of the class described which are adapted to be used with guy rods adapted to receive two or three cables. The present application is based upon the embodiment of the invention shown in Figs. 1 to 6, and the other modifications are made the subject of divisional applications.

Other objects and advantages of the invention will be apparent from the following description and the accompanying drawings, in which similar characters of reference indicate similar parts throughout the several views.

Referring to the three sheets of drawings accompanying the specification:

Fig. 1 is a vertical sectional view taken on a plane at right angles to the surface of the ground and parallel to a guy rod showing a guy rod and guy cable installation which is equipped with the present clamping device;

Fig. 2 is a full size side elevational view of a guy rod grounding clamp constructed according to the present invention;

Fig. 3 is an end elevational view of the upper part of the grounding clamp;

Fig. 4 is an enlarged sectional view taken on a plane passing through the axis of the guy rod and the center of the cable, with the cable and bolt in elevation;

Fig. 5 is a view in perspective of one of the clamping members;

Fig. 6 is an end elevational view of the clamping member of Fig. 5.

Fig. 7 is a view similar to Fig. 4 showing another modified form of clamping device;

Fig. 8 is a side elevational view of the clamping member;

Fig. 9 is an end plan view of the clamping member of this modification;

Fig. 10 is a view similar to Fig. 3 of another modification in which the electrical connector is used with a guy rod having grooves for two cables;

Fig. 11 is a top plan view of the clamping member of this modification;

Fig. 12 is a side elevational view of the clamping member of this modification;

Fig. 13 is a view similar to Fig. 3 of another modification in which the guy rod is provided with grooves for three cables;

Fig. 14 is a bottom plan view of the clamping member used in this modification; and

Fig. 15 is a side elevational view of the clamping member used in this modification.

The present guy rod grounding clamp is particularly adapted to be used on electrical systems employing a grounded neutral conductor that is connected electrically to the various guy wires.

This is done to increase the grounding efficiency, and naturally the insulators in the guy are eliminated. The clamp is adapted to afford a positive contact between the guy wire and the anchor rod, in order to assure a good electrical connection and a better ground for the various guys.

Referring to Fig. 1, 10 indicates the terrain in which there is an installation, comprising an

anchor 11 and a guy rod 12. The anchor and the lower end of the guy rod may be of any of the various types, such as the expanding anchors, cone anchors, dead man anchors, etc., and the lower end of the guy rod may be provided with a point and a head, or may be threaded and provided with a nut 13 (Fig. 2).

The guy, consisting of a steel cable 14, preferably galvanized, has its lower end passed through the eye 15 of the anchor rod, and the free end is secured above the eye 15 by means of any suitable type of cable clamp 16.

Referring to Figs. 2 to 4, these figures show the construction of the guy rod eye and the grounding clamp. The eye is preferably, but not necessarily, provided with a slightly convex impact surface 17 at its upper end, for engagement with the sledge, in the event the anchor rod 12 is to be driven into the earth after it has served its purpose.

The cable 14 passes through the eye 15 and is adapted to engage in a groove 18 of substantially circular cross section, which is also a substantial fit about the periphery of the cable 14; that is, the radius of the groove 18 is substantially equal to that of the cable 14.

The circular groove 18 is curved about a yoke 19, which has an inner surface 20 that may be substantially cylindrical in cross section, as shown in Fig. 4; so as to provide a curve of increased perimeter, about which the cable is bent.

The gradual curve 20 about the yoke 19 prevents the cable from bending sharply and tends to prevent flattening of the cable, and it lessens the difference in strain between the inner strand of the cable and the outer strands at the point of curvature. Together the substantially circular groove 18 and the gradual curve 20 in the eye 15 are adapted to maintain the shape of the cable at the eye such that it has a greater strength and is adapted to perform its functions for a longer period of time under greater loads than any devices which are otherwise constructed.

The eye 15 of the guy rod is preferably slightly elongated in a vertical direction over the devices of the prior art, so as to provide room for a threaded bolt 21 extending through the eye and through the clamping members 22, 23. In order that the bolt 21 may have a firm seat in the eye 15, and to prevent teetering, the lower surface 24 of the eye may be substantially half cylindrical and of a size to be complementary to the external surface of the bolt 21. The space between the cable 14 and the surface 24 may be such that it is just sufficient to receive the bolt 21, or it may be larger.

The clamping members 22 and 23 may be identical in shape and construction, but are reversed as to location. Each of these clamping members comprises a cast metal member having a substantially cylindrical lower body 25, which is provided with a cylindrical through bore 26, having a loose fit on the bolt 21.

The cylindrical body 25 may be extended laterally at 27 and longitudinally at 28 to provide stock for a clamping jaw 29, which has a substantially circular groove 30 extending longitudinally of its outer surface. The circular groove 30 may terminate short of the flat sides 31, 32 of the clamping member so as to leave a pair of surfaces 33 at each side of the groove, and the groove is preferably curved longitudinally, as shown, at its line of contact 34 with the cable 14, in Fig. 4, so as to have the clamping sur-

face 30 a substantial fit with the longitudinally and laterally curved cylindrical surface of the cable 14 in the eye.

In particular, the clamping surfaces or grooves 30 of the clamping members 22 and 23 are characterized by the absence of any sharp corners which might engage the cable and tend to cut or destroy any of its strands or wires. As the longitudinal extension 28 of the clamping member is narrower than the main body 25, it is adapted to be inserted into the eye space 15 in its engagement with the cable 14.

The assembly is made as shown in Figs. 3 and 4, where the head 35 of the bolt engages the flat outer surface 36 of the clamping member 22, and urges it into engagement with the cable at one side, and the spring washer 37 and nut 38 engage the outer surface 36 of the other clamping member 23, and urge it into engagement with the other side of the cable 14.

The grooves 30 in the clamping members 22, 23 naturally tend to prevent rotation of the clamping members on the bolt 21, and the nut 38 on the bolt may be tightened up on the threaded end 39 of the bolt to drive the clamping members into tight engagement with the cable.

Referring to the drawings (Figure 7), this is a modification in which a slightly different form of clamping member is employed. In this case the clamping member comprises a member, most of the surface of which is substantially frusto-conical. Thus, the clamping members 50 and 51 of this embodiment are again identical and they are provided with the external frusto-conical surface 52. The ends 53 and 54 may be flat and each clamping member may be formed with a centrally located through-bore 55 for passing a similar bolt 21.

The clamping member is, however, preferably provided with a pair of laterally projecting ribs 56 and 57 which form the borders of a groove 58 which is partially circular in cross-section. Like the groove 30 previously described, the groove 58 is substantially complementary to the cable with which this connector is employed.

The element of the groove which is indicated by the line 59 in Fig. 8 may be one of the elements of the cone of which the frusto-conical surface 52 is a more complete development. It should also be noted that the frusto-conical surface 52 connects with the relatively flat side surfaces 60 and 61 on both sides of the clamping member so as to give the clamping member sufficient body to reinforce the walls of the groove 58.

In this embodiment of the invention the groove 58 is not curved longitudinally of its surface which engages the cable, but is substantially cylindrical. This gives a reduced area of contact between the walls of the groove 58 and the cable, but sufficient pressure may be exerted by means of the threaded bolt 21 to get a good electrical contact. In some other embodiments of the invention the groove 58 might be eliminated so that the clamping member would be a simple frusto-conical wedging member.

In the embodiment of Figs. 7 to 9, the clamping member also has a partially cylindrical surface 62 joining with the flat side surfaces 60. The operation of this connector is substantially the same as that of Figs. 1 to 6 except that the eye of the guy rod in this case may be larger in relation to the size of the clamping member and the clamping member itself may extend into the eye.

in such manner that the frusto-conical surfaces 52 on the two clamping members engage that portion of the eye opposite to the cable as shown in Fig. 7.

In other embodiments of the invention, where the eye of the guy rod is smaller and there is room only for the bolt and the cable therein, the frusto-conical surface 52 may not engage the lower part of the eye, but the clamping members may be spaced farther apart like the clamping members 22 and 23 of Fig. 4.

Referring to Figs. 10 to 12, these views show another modification of the connector peculiarly adapted to be used with a guy rod having grooves for two cables. Like the arrangements previously described, this modification includes two clamping members 63, 64 of similar shape oppositely disposed on the bolt 21. Each clamping member may consist of an integral metal body having the inner and outer plane surfaces 65, 66 and provided with a through-bore 67 adapted to receive the bolt 21.

These clamping members 63 or 64 are also preferably provided with a frusto-conical surface 68 adapted to be wedged into the eye of the guy rod when the clamping member is installed according to Fig. 7. The clamping member 63 is also provided with a partially cylindrical surface 70 and with the laterally projecting ribs 71, 72, 73, which are separated by the grooves 74, 75.

Grooves 74, 75 are substantially cylindrical in form and are separated by the rib 72 which is of such width with relation to the separation between the grooves of the guy rod eye that grooves 74 and 75 are located to engage the cables when they are properly located in the grooves of the eye as shown in Fig. 10. The sides 76, 77 of this member 63 taper gradually from the ribs 71, 73 toward the frusto-conical surface 68.

I desire it to be understood that in other embodiments of the invention, the grooves 74 and 75 may be curved longitudinally of the cable, as shown in the embodiment of Fig. 5, instead of being cylindrical. The longitudinal curvature of the groove gives it a greater area of contact with the cable and permits a tighter clamping action without possibility of damage to the cable.

Referring to Figs. 13 to 15, these are views showing such a connector adapted to be used with a guy rod having three cable grooves and arranged for use with three cables. In this case the clamping members 80 and 81 are again identical in construction and each may comprise an integral metal member provided with the upper and lower plane surfaces 82 and 83. The body of the clamp may have a frusto-conical surface 84 and a cylindrical surface 85 and a through-bore 86 adapted to receive the bolt 21.

In this embodiment the clamping surface of the member 80 is provided with the three grooves 87, 88, 89, and with the four laterally projecting ribs 90, 91, 92, 93. Due to the location of the central cable groove in the guy rod eye, the ribs 91 and 92 project outward farther than the ribs 90 and 93 and the groove 88 is located to engage the central cable at the same time the grooves 87, 89 engage the two side cables. Again the shape and location of the grooves are determined by the shape and location of the cables when they are installed in the eye.

The clamping member has its clamping surfaces preferably formed substantially complementary to the innermost surfaces of the cables when installed in the eye. This would necessitate making the grooves curved longitudinally as

well as laterally, but in some embodiments of the invention the grooves 87, 88, 89, may be simple, cylindrical grooves.

The clamping members in this case may be arranged as shown in Fig. 4 with the clamping members merely engaging the cables and bolt, or they may be arranged as shown in Fig. 10 with the frusto-conical surface of the clamping members in wedging engagement with that portion of the eye that is opposite to the cable grooves of the eye.

One of the most important features of the invention lies in the wedging action between the cable eye and the clamping members and the cables, which assures a tight electrical contact, and this wedging action is brought about by tightening the bolt which holds the two clamping members in the eye against the cable or cables.

The wedging action is present between the cable and the clamping members in both types of installation, such as that of Fig. 4 where the clamping members are wholly supported on the bolt, and that of Fig. 10 where the clamping members have their frusto-conical surfaces wedged into the eye of the guy rod. In the latter case there is less tendency toward the bending of the bolt, but the installation has a more rigid characteristic, whereas in the installation according to Fig. 4, the longitudinal resiliency of the bolt may be brought into play for holding the clamping members resiliently against the cable.

It will thus be observed that the present electrical connectors may be made in forms suitable for application to guy rods having one cable, two cables, or three cables.

As the clamping members fit the cable and as the groove 18 in the eye fits the cable, the tight mechanical and electrical contact between the cable and the guy rod is provided without any danger of deforming the cable or damaging its strands or wires.

The ground clamp is adapted to provide further assurance against loose guys because it assists the cable clamp 16. The tight electrical and mechanical contact which is provided by this grounding clamp is independent of the strain or slack in the guy wire, and a good ground is assured through the guy rod and anchor under all conditions.

Because of the firm gripping action between the grounding clamp cable and the guy rod, vibration no longer produces an abrasive action between the guy cable and the anchor rod and the galvanized covering of the guy strand and the guy rod are protected against abrasion at their points of mutual contact. The lock washer on the bolt of the grounding clamp provides a measure of resilient clamping action between the clamping members and the cable, and prevents the nut from loosening due to vibration.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. A guy rod grounding clamp structure comprising a bolt adapted to be passed through the eye of a guy rod, said bolt having means at its

ends for engaging a pair of clamping members, and a pair of clamping members carried by said bolt, each of said clamping members being provided with a through bore for said bolt, and with a groove of substantially circular cross section complementary in shape to a cable adapted to be used in the eye of said guy rod.

2. A guy rod grounding clamp structure comprising a bolt adapted to be passed through the eye of a guy rod, said bolt having means at its ends for engaging a pair of clamping members, and a pair of clamping members carried by said bolt, each of said clamping members being provided with a through bore for said bolt, and with a groove of substantially circular cross section complementary in shape to a cable adapted to be used in the eye of said guy rod, said groove being curved longitudinally to correspond substantially to the longitudinal curvature of the cable in the eye.

3. In a grounded guy rod assembly, the combination of a guy rod having an eye at its upper end, said eye being of sufficient size to pass a cable, and a through bolt, and said eye having a surface engaging one side of said bolt, and a pair of clamping members carried by the opposite ends of said bolt, said bolt having a head, and threaded means for driving said clamping members toward each other and toward the yoke of said eye, whereby a cable may be clamped between said clamping members and the yoke of said eye.

4. A guy rod adapted to be grounded, comprising an elongated metal member having a head provided with an eye at one end, the said eye having a yoke provided with a groove of substantially circular cross section, and having an easy longitudinal curvature for engaging a cable, said eye having space to pass a cable and to pass a grounding clamp bolt, the part of said eye adjacent said bolt being formed complementarily to the external surface of said bolt, to provide longitudinal support for the bolt.

5. In an electrical conductor for guy rods and cables, the combination of a threaded member adapted to extend through the eye of a guy rod and a pair of clamping members having apertures for receiving said threaded member, said clamping members being arranged on the opposite sides of said guy rod and said clamping members having wedging surfaces for engagement with the cable in said guy rod whereby said threaded member may draw the clamping members into tight electrical wedging engagement with the cable.

6. In an electrical connector for guy rods and cables, the combination of a threaded member adapted to extend through the eye of a guy rod and a pair of clamping members having apertures for receiving said threaded member, said clamping members being arranged on the opposite sides of said guy rod and said clamping members having wedging surfaces for engagement with the cable carried by said guy rod whereby said threaded member may draw the clamping members into tight electrical wedging engagement with the cable, said wedging surfaces being curved laterally to correspond substantially to the lateral curvature of the cable in said guy rod.

7. In an electrical connector for guy rods and cables, the combination of a guy rod having an eye with cable means located in said eye and a bolt passing through said guy rod, said bolt having a pair of clamping members arranged on said bolt on opposite sides of said guy rod and said

clamping members having wedging surfaces adapted to engage said cable means, and threaded means on said bolt whereby the clamping means may be drawn into wedging engagement with said cable.

8. In a guy rod grounding clamp, the combination of a guy rod having an eye, said eye being provided with a groove for receiving a cable and a grounding clamp comprising a bolt passing through the eye, said bolt having mounted upon it a pair of clamping members, one at each side of said eye, and said clamping members having surfaces for engaging the side of said cable passing through said eye.

9. A guy rod grounding clamp structure comprising a bolt adapted to be passed through the eye of a guy rod, said bolt having means at its ends for engaging a pair of clamping members, and a pair of clamping members carried by said bolt, each of said clamping members being provided with a through bore for said bolt, and with a groove of substantially circular cross section complementary in shape to a cable adapted to be used in the eye of said guy rod, each of said clamping members comprising a body portion surrounding said bolt and provided with an outer thrust surface, said body portion having on one side an axial extension provided with said groove.

10. A guy rod grounding clamp structure comprising a bolt adapted to be passed through the eye of a guy rod, said bolt having means at its ends for engaging a pair of clamping members, and a pair of clamping members carried by said bolt, each of said clamping members being provided with a through bore for said bolt, and with a groove of substantially circular cross section complementary in shape to a cable adapted to be used in the eye of said guy rod, each of said clamping members comprising a body portion surrounding said bolt and provided with an outer thrust surface, said body portion having on one side an axial extension provided with said groove, said axial extension having a groove engaging the side of said bolt.

11. A guy rod grounding clamp structure comprising a bolt adapted to be passed through the eye of a guy rod, said bolt having means at its ends for engaging a pair of clamping members, and a pair of clamping members carried by said bolt, each of said clamping members being provided with a through bore for said bolt, and with a groove of substantially circular cross section complementary in shape to a cable adapted to be used in the eye of said rod, each of said clamping members comprising a body portion surrounding said bolt and provided with an outer thrust surface, said body portion having on one side an axial extension provided with said groove, said groove being inclined toward the axis of said bolt at its inner end to provide a portion of outwardly increasing thickness between the bolt and the cable.

12. A clamping member for guy rod grounding clamps, comprising a substantially cylindrical metal member having a through bore extending longitudinally of said member, said member having a longitudinal extension adapted to extend into the eye of a guy rod, and said extension having on its outer surface a groove that is substantially circular in cross section, for engaging a cable in the eye of the guy rod, the said groove being curved longitudinally in substantially the same direction as the curvature of the cable in the eye of the guy rod.

DAVID C. HUBBARD.
